UNITED STATES PATENT OFFICE.

JACOB M. NABSTEDT, OF DAVENPORT, IOWA.

DESIGN FOR A BADGE.

SPECIFICATION forming part of Design No. 31,778, dated November 7, 1899.

Application filed October 2, 1899. Serial No. 732,424. Term of patent 14 years.

To all whom it may concern:

Be it known that I, JACOB M. NABSTEDT, a citizen of the United States, residing at Davenport, county of Scott, and State of Iowa, 5 have invented and produced a new and original Design for Badges, of which the following is a specification, reference being had to the accompanying drawings, forming part hereof.

Figure 1 is a plan view of a badge, showing 10 the face of my new design. Fig. 2 is a sectional view of the design, taken on the line X X of Fig. 1.

As shown in the drawings, the leading or 15 material feature of my design consists of the partial figure of an elk standing with head and horns upraised, the raised face of the de-

sign showing a side view of an elk, the back of the design being flat.

Fig. 2 shows the elevation of the figure, the horns A, the nose B, the breast C, and the 20 legs D.

It is apparent that this design is also applicable to other similar articles.

Having described my invention, what I claim as new, and desire to secure by Letters 25 Patent, is—

The design for a badge as herein shown and described.

JACOB M. NABSTEDT.

Witnesses:

ALWINE NABSTEDT,
A. G. BUSH.
